10 Claims

ABSTRACT OF THE DISCLOSURE

New compositions of matter and method of administration are described. The compositions contain as the active components 2-nitro-1,3,4-thiadiazole and 5-substituted derivatives thereof. The compositions are useful as topical antifungal agents.

SUMMARY OF THE INVENTION

This invention relates to new pharmaceutical compositions of matter and methods of administration to warm-blooded animals. More specifically, the invention relates

2

amino, morpholino, 2 - (methylthio) - 2 - imidazolin-1-yl, phenylthio and phenylsulfonyl.

The active ingredients of the compositions of this invention are, in general, yellow or orange colored, crystalline solids having characteristic melting points. They are relatively soluble in many organic solvents, such as, lower alkanols, acetone, ethyl acetate, and the like. Generally, however, they are insoluble in water.

The active ingredients of the compositions of this invention have shown high activity against a variety of fungi. The *in vitro* antifungal activity of representative compounds is presented in Table I below which shows the minimal inhibitory concentration required to inhibit the growth of representative microorganisms in a nutrient medium.

medium.

Additionally, the compounds of this invention have been found to be active against *Microsporum canis* when tested in guinea pigs. Briefly, the test is described as follows: Male albino guinea pigs, 300-500 g. (five animals per test group and five controls) are infected dermally with 0.5 ml. of a 10^{-1} dilution of a standard *M. canis* infective hair suspension. The test compounds are incorporated into ointments at concentrations of 5, 1, 0.25, and 0.06 percent in a mixture of solid polyethylene glycols having a molecular weight averaging about 400 and about 4,000.

TABLE I.—IN VITRO ANTI-FUNGAL ACTIVITY (MINIMAL INHIBITORY CONCENTRATIONS) (MCG./ML.)

Compound Name	Organism ¹											
	1	2	3	4	5	6	7	8	9	10	11	12

to new compositions useful as topical antifungals containing as the active ingredient a compound of the formula:

wherein R is hydrogen, lower alkyl, phenyl, p-methoxyphenyl, p-formylphenyl, p-carboxyphenyl, p-nitrophenyl, p-tolyl, p-benzalacetate, bromo, amino, diloweralkyl-

Griseofulvin (1 percent) in the same polyethylene glycol mixture is included in the procedure as a positive control. Treatment is applied to the infected lesion once daily for 5 days starting on day 3 postinfection. About 0.5 g. of ointment containing a particular test compound is applied topically at each treatment. Test animals are scored on day 10 and 17 postinfection as to the relative concentration of viable organisms per hair sample. Table II lists the results obtained with representative compounds of the present invention.

TABLE II.—HAIR CULTURE SCORES OF TEST COMPOUNDS TESTED IN THE *M. canis* INFECTION IN GUINEA PIGS

Compound Name	Hair Culture Score, day 10, day 17			
	5%	1%	0.25%	0.06%
2-nitro-1,3,4-thiadiazole.....	++, ++	+, ++	+, ++	++, +++
2-nitro-1,3,4-thiadiazole (repeat)	0, ++	+, ++	+, ++	++, +++
2-phenyl-5-nitro-1,3,4-thiadiazole.....	0, ++	+, ++	+, ++	NT
2-methyl-5-nitro-1,3,4-thiadiazole.....	NT	++, ++	++, ++	NT

2-(p-methoxyphenyl)-5-nitro-1,3,4-thiadiazole.....	NT	NT	++, +++	NT
5-nitro-2-bromo-1,3,4-thiadiazole.....	+, ++	NT	NT	NT
Griseofulvin (combined results).....	NT	0, +	+, ++	++, +++
Control (combined results).....		++++, +++++	++++, +++++	++++, +++++

Hair culture score indicates the concentrations of viable spores per hair sample (0; + = 1-10; ++ = 11-100; +++ = 101-1,000, and ++++ = 1,000). The hair culture score at the beginning of the treatment the third day after infection, ranged from + to ++++. NT indicates not tested.

The excellent activity against dermatophytic Trichophyton and Microsporum species (see Tables I and II), coupled with the relative chemical stability of the compounds of this invention, make them useful in the treatment of fungal infections of the skin of warm-blooded animals. For such use these compounds may be formulated with appropriate topically useful carriers such as wetting agents, stabilizing agents, dusting powders, ointments, creams, lotions, etc. The formulated compounds can be applied topically to the infected skin area. The topical compositions may contain from 0.2% to 5% of active component with a topically acceptable carrier.

The compounds of the present invention can be prepared by methods described herinafter in the examples and in the prior art. The method most general for preparing the majority of the compounds is by the conversion of the amino group of the substituted 5-amino-1,3,4-thiadiazole to a nitro group proceeding by the intermediate diazonium salt. Details are described in the examples.

The invention will be described in greater particularity in conjunction with the following specific examples.

EXAMPLE 1

Preparation of 2-phenyl-5-nitro-1,3,4-thiadiazole

A mixture of 9.0 g. (0.05 mole) of 2-amino-5-phenyl-1,3,4-thiadiazole [prepared as described in Chem. Ber. 96, 1059 (1963)], 85 ml. of 40% fluoroboric acid and 50 ml. of water is heated to give a clear solution. This mixture is added, during a 20 minute period, to a stirred suspension of 10 g. (0.126 mole) of cupric oxide, 28 g. (0.4 mole) of sodium nitrite and 80 ml. of water which has been treated with 1 to 2 drops of fluoroboric acid 15 minutes before addition of the amine. After the mixture is stirred for 2.5 hours the solid is collected and dried, then extracted with methylene chloride. The extracts are concentrated to a small volume and chromatographed on an aluminum oxide column using methylene chloride as eluant, yield 1.6 g. of crude material. The crude material is recrystallized from methylene chloride and petroleum ether to give 1.1 g. (10% yield) of product, melting point 158-160° C.

EXAMPLE 2

Preparation of 2-phenyl-5-nitro-1,3,4-thiadiazole

The cupro-cupri sulfite is prepared by adding a solution of 25.2 g. (0.20 mole) of anhydrous sodium sulfite in 400 ml. of water to a solution of 33.6 g. (0.21 mole) of anhydrous cupric sulfate in 400 ml. of water. The mixture is magnetically stirred at room temperature for 30 minutes, and filtered through a layer of diatomaceous earth covered with a piece of filter paper. The red-brown cupro-cupri sulfite is washed with three 200 ml. portions of water. The cupro-cupri sulfite is removed from the funnel and slurried with 300 ml. of water. This mixture is filtered through a layer of diatomaceous earth (covered with filter paper), and the cupro-cupri sulfite is washed with another 600 ml. of water. The thoroughly washed cupro-cupri sulfite is slurried in 200 ml. of water, and the mixture is added to a solution of 40 g. (0.58 mole) of sodium nitrite in 100 ml. of water. A warm solution of 35.4 g. (0.20 mole) of 2-amino-5-phenyl-1,3,4-thiadiazole in 100 ml. of fluoroboric acid (37-40%) and 150 ml. of water is added slowly (about 10 ml. portions) to the mechanically stirred mixture of cupro-cupri sulfite and sodium nitrite in a three-necked 3-liter flask. Foaming occurs after each addition, and either is added to break the foam. The addition takes about one hour. The mixture is then stirred for 2 hours with no external heating. The reaction temperature rises to 35° C. and then slowly drops to 25° C. The mixture is filtered, and the solid and the filtrate are extracted with three 250 ml. portions of benzene. The benzene extract is dried, decolorized and evaporated to leave 10.3 g. of crystalline residue. A solution of the residue (10.3 g.) in 200 ml. of benzene is

chromatographed on an activated magnesium silicate column. The column (3.8 x 36 cm.) is prepared from 200 g. of 60-200 mesh activated magnesium silicate slurry packed in benzene. The column is eluted with 1700 ml. of benzene, and 100 ml. fractions are collected. Fractions 6 through 15 are combined and evaporated to give 3.4 g. (8% yield) of pale yellow crystals. One recrystallization from 300 ml. of methanol yield 1.6 g. (4%) of 2-phenyl-5-nitro-1,3,4-thiadiazole, melting point 157-159° C.

EXAMPLE 3

Preparation of 2-(p-methoxyphenyl)-5-nitro-1,3,4-thiadiazole

To 7 g. of 2-amino-5-p-methoxyphenyl-1,3,4-thiadiazole, and 14.8 g. of warm 50% fluoroboric acid hot water is added until the solution is practically clear. Insoluble material is filtered off and the solution is heated on the steam bath until its temperature is approximately 80° C. It is then added rapidly in portions, with good stirring to a mixture of 16.2 g. of sodium nitrite, 2.65 g. copper oxide, 2.13 g. copper in 60 ml. of water, in a 3-neck flask at 80° C. After 20 minutes between 80-97° C., the solid is collected from the hot mixture. The solid is dissolved in methylene chloride and the solution filtered to separate the insoluble material. The methylene chloride solution is dried over magnesium sulfate and filtered. The filtrate is concentrated and chromatographed on an alumina oxide column using methylene chloride as eluting solvent. The product obtained is washed with ether-petroleum ether (boiling point 30°-60° C.): Yield, 1.25 g. (15.7%), melting point 181-183.5° C.

EXAMPLE 4

Preparation of 2-p-tolyl-5-amino-1,3,4-thiadiazole

A mixture of 58.2 g. (0.29 mole) of ethyl p-methylbenzimidate hydrochloride, 22.1 g. (0.242 mole) of thiosemicarbazide and 300 ml. of pyridine is heated to boiling in an open flask for 1.75 hours. The flask, which then contains very little solvent, is cooled and ice water is added. The solid which has formed is collected by filtration, washed with water, slurried with ether and the mixture is filtered again; yield, 24.3 g., melting point 195-205° C. After recrystallization from acetonitrile, 16.5 g. (36% yield) of the purified product is obtained, melting point 215-219° C.

EXAMPLE 5

Preparation of 2-p-tolyl-5-nitro-1,3,4-thiadiazole

A hot solution of 3.82 g. (0.02 mole) of 2-p-tolyl-5-amino-1,3,4-thiadiazole, 8.8 g. of 50% fluoroboric acid and 40 ml. of acetic acid is added dropwise, but rapidly, to a vigorously stirred suspension of 10 g. of sodium nitrite, 40 ml. of water, 1.2 g. of copper powder and 1.4 g. of cupric oxide at 80° C. (Two or three drops of 50% fluoroboric acid had been added to the latter suspension immediately preceding the addition.) A concentrated aqueous solution of 5 g. of sodium nitrite is added and the mixture is stirred at 70-85° C. for 2 hours. The mixture is cooled, diluted with water and filtered and the solid, after drying, is extracted with ether. The ether extracts are evaporated to dryness and the residue is chromatographed on alumina oxide using methylene chloride as carrier solvent; yield 1.3 g. (14%), melting point 177-179° C. A sublimed sample melts at 179-182° C. In a number of runs, the yield has varied from 14 to 22%.

EXAMPLE 6

Preparation of 4-[5-nitro-1,3,4-thiadiazole-2-yl]-benzalacetate

126 mg. (0.0005 mole) of 2-tolyl-5-nitro-1,3,4-thiadiazole in 3 ml. of acetic anhydride is cooled and treated with 0.2 ml. of concentrated sulfuric acid and stirred a few minutes while cooling below 10° C. A mixture of 139 mg. of chromium trioxide in 4 ml. of acetic anhydride

is added dropwise with constant stirring below 10° C. After 2 hours, the addition of ice water produces a solid which is collected, washed with water, slurried in 2% sodium carbonate and again washed with water; yield 118 mg., melting point 168-177° C. Recrystallization from benzene-hexane gives a pure product; yield, 42 mg. (25%), melting point 184-187° C.

EXAMPLE 7

Preparation of 2-methyl-5-nitro-1,3,4-thiadiazole

A solution of 2.88 g. (0.024 mole) of 2-amino-5-methyl-1,3,4-thiadiazole in 4.5 g. (3.4 ml.) of 48-50% fluoboric acid is diluted with an additional 13 ml. of the fluoboric acid, and the solution cooled to 0-5° C. Sodium nitrite, 1.67 g. (0.024 mole) is added slowly during fifteen minutes. The red slurry is stirred at 0-5° C. for an additional twenty minutes, and is then added in small portions to a vigorously stirred suspension of 4.9 g. (0.077 atom) of copper powder in a solution of 24.7 g. (0.36 mole) of sodium nitrite in 50 ml. of water (temperature, 25° C.). The addition requires twenty minutes, and a noticeable amount of nitrous oxide is liberated during the addition. The reaction mixture becomes green during the addition, and is accompanied by vigorous gas evolution (ether is used to break the foam). After thirty minutes, gas evolution is no longer evident. The reaction mixture is filtered and the filtrate is extracted with three 150 ml. portions of benzene. The benzene extracts are combined and dried over magnesium sulfate. Removal of the benzene under reduced pressure gives 1.75 g. (50% crude yield) of a yellow syrup that crystallizes on standing. Recrystallization from 50% aqueous acetone yields 0.95 g. (27%) of pure product, melting point 65-66° C.

EXAMPLE 8

Preparation of 2-n-butyl-5-nitro-1,3,4-thiadiazole

The cupro-cupri sulfite is prepared from a solution of 8.85 g. (0.07 mole) of anhydrous sodium sulfite in 200 ml. of water and 12.0 g. (0.075 mole) of anhydrous cupric sulfate in 200 ml. of water as described in Example 2. The cupro-cupri sulfite is slurried in 100 ml. of water and the mixture is added to a solution of 12.5 g. (0.18 mole) of sodium nitrite in 100 ml. of water in a three-necked 2-liter flask fitted with a mechanical stirrer and a thermometer. A solution of 10.0 g. (0.06 mole) of 2-amino-5-n-butyl-1,3,4-thiadiazole in 80 ml. of fluoboric acid is added dropwise during 20 minutes. The reaction temperature rises from 18° to 30° C. The mixture is stirred for 30 minutes, and is then filtered. The solid and the filtrate are extracted with three 250 ml. portions of benzene and the extracts are washed with water. Magnesium sulfate and activated charcoal are added, and the mixture is filtered. Evaporation of the benzene leaves 7.2 g. of a brown oil which is dissolved in 200 ml. of benzene. The benzene solution is chromatographed on an activated magnesium silicate column (3.8 x 36 cm.) which is prepared from 200 g. (60-200 mesh) activated magnesium silicate slurry packed in benzene. Fractions of 100 ml. are collected, and the column is developed with 2 liter of benzene. Fractions 7 through 20 are combined and evaporated to leave 1.3 g. (10% yield) of a yellow oil. The product is recrystallized twice from ether-hexane (at -10° C.) to give 100 mg. (1% yield) of 2-n-butyl-5-nitro-1,3,4-thiadiazole, melting point approximately 20° C.

EXAMPLE 9

Preparation of 2-bromo-5-nitro-1,3,4-thiadiazole

900 mg. (0.005 mole) of 2-amino-5-bromo-1,3,4-thiadiazole, 1 ml. of concentrated hydrochloric acid and 2 ml. of water are mixed and heated on the steam bath to dissolve. This solution is added dropwise in a 15 minute period to a vigorously stirred suspension of copper metal powder in a solution of 1 g. sodium nitrite (0.015 mole)

in 10 ml. of water. [The sodium nitrite, copper is first treated with one or two drops hydrochloride acid to initiate nitrous oxide and stirred 15 minutes before starting the addition described above.] During addition, the mixture becomes green, evolves gas, and a yellow solid separates. The mixture is stirred for 2 hours, filtered and the solid is dried. The solid is extracted with ether. Evaporation of the ether gives 500 mg. of dark yellow crystals, melting point 102-103° C. Recrystallization gives 450 mg. (43%) of product, melting point 102-103° C.

EXAMPLE 10

Preparation of 2-dipropylamino-5-nitro-1,3,4-thiadiazole

A solution of 6.1 g. (0.06 mole) of di-n-propylamine in 50 ml. of ether is added dropwise during 10 minutes to a suspension of 6.3 g. (0.03 mole) of 2-bromo-5-nitro-1,3,4-thiadiazole in 700 ml. of ether in an ice bath at 20° C. The mixture is magnetically stirred at 20° C. for 30 minutes, and the di-n-propylamine hydrochloride is removed by filtration. The ether filtrate is washed with saturated sodium chloride solution, dried and decolorized. Evaporation of the ether gives 1.9 g. of a red oil which is dissolved in 50 ml. of benzene. The benzene solution is placed on an aluminum oxide column. (150 g. aluminum oxide slurry packed in benzene to give a column 2.7 x 27 cm.). The development of the column with 250 ml. of benzene gives 4.2 g. of a yellow oil. A solution of this oil in 100 ml. of ether and 100 ml. of hexane is chilled in a Dry Ice-acetone bath. The resulting yellow crystals are collected (at 5° C.) by filtration and are washed with cold hexane. The crystals melted at 15° C. The resulting yellow oil, 2.8 g. (40% yield) is dried under reduced pressure at 25° C. over phosphorus pentoxide and paraffin.

EXAMPLE 11

Preparation of 2-morpholino-5-nitro-1,3,4-thiadiazole

A solution of 1.9 ml. (0.022 mole) of morpholine in 15 ml. of ether is added dropwise during 20 minutes to a solution of 2.1 g. (0.01 mole) of 2-bromo-5-nitro-1,3,4-thiadiazole in 75 ml. of ether. The resulting yellow mixture is stirred at room temperature for 2 hours and filtered. The yellow precipitate is washed with ether and water and air dried to give 1.65 g. of a yellow solid, melting point 149-152° C. This material is recrystallized twice from ethanol to yield 1.46 g. (68%) of pure product, melting point 151-152° C.

EXAMPLE 12

Preparation of 2-dimethylamino-5-nitro-1,3,4-thiadiazole

A solution of 2.1 g. (0.01 mole) of 2-bromo-5-nitro-1,3,4-thiadiazole in 150 ml. of ether is chilled in a salt-ice bath, and 5.0 ml. (0.75 mole) of dimethylamine is added. The mixture is stirred (salt-ice bath cooling) for 2 hours and then filtered. The orange precipitate is washed with ether and water and dried yielding 1.3 g. of the crude product, melting point 138-140° C. An additional 0.3 g. orange crystals, melting point 139-142° C. is obtained from the filtrate. The two solids are combined and recrystallized twice from ethanol to yield 1.1 g. (63%) of the purified compound, melting point 141.5-142.5° C.

EXAMPLE 13

Preparation of 2-amino-5-nitro-1,3,4-thiadiazole

Ammonia is bubbled through a magnetically stirred solution of 4.2 g. (0.02 mole) of 2-bromo-5-nitro-1,3,4-thiadiazole in 100 ml. of dioxane. The dioxane had been purified by passing it through an aluminum oxide column before use. After fifty minutes, the mixture is filtered. The brown precipitate is washed with ether and water and dried at 50° C. to give 1.36 g. (46%) of crude product, melting point decomposition above 230° C. (capillary). A sample prepared in a similar experiment is recrystallized once from water and twice from ethyl acetate to

give pale yellow crystals, melting point decomposition above 230° C. with previous sintering above 205° C.

EXAMPLE 14

Preparation of 2-[2-(methylthio)-2-imidazolin-1-yl]-5-nitro-1,3,4-thiadiazole

A solution of 9.5 g. (54 mmoles) of 2-bromo-5-nitro-1,3,4-thiadiazole in 150 ml. of benzene is added during 10 minutes to a stirred solution of 10.6 g. (92 mmoles) of 2-methylthioimidazoline in 200 ml. of benzene. The mixture is stirred under nitrogen at 22-27° C. for 3.5 hours. The mixture is filtered, and the benzene filtrate washed with water and saturated sodium chloride solution. The benzene layer is dried, decolorized, and evaporated to leave 12.7 g. of red crystalline residue. The residue is triturated with methanol to yield 4.2 g. (41%) of yellow crystals, melting point 185-194° C. The analytical sample was recrystallized twice from acetone, melting point 202-204° C.

EXAMPLE 15

Preparation of 4-(5-nitro-1,3,4-thiadiazol-2-yl)-benzaldehyde

674 mg. (0.002 mole) of 4-[5-nitro-1,3,4-thiadiazol-2-yl]benzaldiacetate (Example 6) is dissolved in hot ethanol, and 15 ml. of water and 0.2 ml. of concentrated sulfuric acid are added to the solution. The suspension is heated to reflux and additional ethanol is added until a clear solution is obtained. The clear solution is heated at reflux temperature for an additional fifty minutes after which time the condenser is removed and the ethanol is removed by evaporation. The yellow solid is collected by filtration while the aqueous solution is hot. The cooled filtrate gives a second crop of product of lesser purity. The first crop of crystals weighs 324 mg. (72.7% yield), melting point 173-175° C. A recrystallization from methylene chloride yields purified 4-(5-nitro-1,3,4-thiadiazol-2-yl)benzaldehyde, melting point 174.5-176° C.

EXAMPLE 16

Preparation of 4-(5-nitro-1,3,4-thiadiazol-2-yl)-benzoic acid

To 170 mg. of 4-(5-nitro-1,3,4-thiadiazol-2-yl)benzaldehyde is added 10 ml. of 40% peroxyacetic acid. The mixture becomes clear on warming over a steam bath, but shortly after a solid precipitates. The suspension is heated 1 hour, diluted with water and the solid collected. The solid is dissolved in 5% sodium bicarbonate, filtered and reprecipitated with 9 M sulfuric acid. 113 mg. of product is obtained which when recrystallized from acetone-acetonitrile and dried, has a melting point of 248-250° C. dec. with eff.

EXAMPLE 17

Preparation of 2-(p-nitrophenyl)-5-nitro-1,3,4-thiadiazole

4 ml. of water, 1.1 g. of sodium nitrite, 144 mg. copper and 180 mg. of cupric oxide are mixed and heated to 80° C. with constant agitation. 504 mg. of 2-(p-nitrophenyl)-5-amino-1,3,4-thiadiazole [see Helv. Chim. Acta 13, 1935 (1950)], 1.0 g. of 48-50% fluoboric acid 4 ml. acetic acid, and 5 ml. water are mixed and heated in a steam bath until a clear solution is obtained. The solution containing the amine is added dropwise but rapidly to the nitrite suspension described above. The resulting suspension is stirred for two and one-half hours at temperatures ranging from 70 to 90° C. At the end of this period the solution is cooled and the solid collected by filtration, washed with water and extracted with several portions of methylene chloride. The methylene chloride extracts are combined and evaporated to a residue which is then slurried several times with ether. The insoluble material is collected, wt. 95 mg. Sublimation of this material at 100-185° C. (0.1 mm.) and washing the sublimate with ether yields the desired 2-(p-nitro-

phenyl)-5-nitro-1,3,4-thiadiazole, melting point 204.5-207° C. Additional product is obtained from residue of the ether wash by sublimation and washing the sublimate with ether. Combined yield of product is 64 mg. (11% yield).

EXAMPLE 18

Preparation of 2-(phenylthio)-5-nitro-1,3,4-thiadiazole

4.2 g. (0.02 mole) of 2-bromo-5-nitro-1,3,4-thiadiazole is dissolved in ethanol and 4.34 g. (0.02 mole) of the silver salt of thiophenol is added. After refluxing 36 hours, the solvent is evaporated and ether added. The insoluble material is filtered off and the filtrate evaporated. The residue is slurried repeatedly with very small quantities of cold ether to wash out impurities. Recrystallization of 2 g. from methylene-chloride ether gives 1.6 g. (33.6%) of analytically pure product, melting point 92-94° C.

The filtrates from washing and recrystallization are combined, concentrated and chromatographed to yield an additional 315 mg. of product. (Total yield 46%).

EXAMPLE 19

Preparation of 2-(phenylsulfonyl)-5-nitro-1,3,4-thiadiazole

104 m. of 2-(phenylthio)-5-nitro-1,3,4-thiadiazole is warmed on the steam bath for 30 minutes in 10 ml. of 40% peroxy-acetic acid. The original yellow solution becomes colorless. It is cooled and then diluted with ice and water to yield 66 mg. (50%) of product; melting point, 121-123°. Analytically pure material, melting point 124-126° C. is obtained either by sublimation [ca. 125° (0.1 mm.)] or recrystallization from ether-hexane.

EXAMPLE 20

The compounds of this invention may be incorporated into a topical jelly according to the following formulation.

Ingredient:	Amount percent w./v.
Substituted 5-nitro-1,3,4-thiadiazole	1.0
Methocel 00	2.75
Parabens (4:1 mixture of methyl and propyl)	0.1
Propylene glycol	20.0
Distilled water, q.s.	100.0

The parabens and methocel are dissolved in about two-thirds of the final volume of distilled water 80° C. with stirring. The gel is cooled to below 40° C. and is then added with stirring to a solution to the active ingredient in propylene glycol. The final gel is adjusted to volume with distilled water.

A 5 ml. portion of this gel contains 50 mg. of active ingredients.

EXAMPLE 21

A cream incorporating a compound of this invention may be formulated as follows:

Ingredient:	Amount percent w./v.
Substituted 5-nitro-1,3,4-thiadiazole	2.0
Liquid petrolatum (light)	20.0
Cetyl alcohol	5.0
Parabens (4:1 mixture of methyl and propyl)	0.1
Emulsifier	5.0
Glycerin	5.0
Distilled water, q.s.	100.0

The parabens are dissolved in about two-thirds of the final volume of distilled water at 80° C. with stirring. The solution is cooled to about 50° C. and glycerine is added. Light liquid petrolatum, cetyl alcohol and emulsifier are heated together to about 50° C., blended well, and added with stirring to the warm aqueous solution. The emulsion is cooled to room temperature and the

active ingredient is then added with stirring. The volume is adjusted with distilled water.

EXAMPLE 22

The compounds of this invention may be incorporated into a topical carbowax base ointment according to the following formulation.

Ingredient:	Amount percent w/v.
Substituted 5-nitro-1,3,4-thiadiazole	1.0
Polyethylene glycol having molecular weight of 400	32.0
Polyethylene glycol having molecular weight of 4000 q.s.	100.0

The vehicles are blended together at about 60-65° C. The active ingredient is suspended in the mixture with stirring and the slurry is passed through a suitable mill. The ointment is agitated while cooling to room temperature to assure homogeneity.

EXAMPLE 23

The compounds of this invention may be incorporated into a topical grease-base ointment according to the following formulation.

Ingredient:	Amount percent w/v.
Substituted 5-nitro-1,3,4-thiadiazole	2.0
Lanolin U.S.P.	10.0
White petrolatum U.S.P., q.s.	100.0

The white petrolatum and lanolin are melted at 50-60° C. and blended together. The active ingredient is suspended in the mixture with stirring and the slurry is passed through a suitable mill. The ointment is agitated while cooling to room temperature to assure homogeneity.

We claim:

1. A fungicidal composition in the form of ointments, dusting powders, creams and lotions for controlling fungi consisting essentially of a topically acceptable carrier and from 0.2% to 5% of a nitrothiadiazole of the formula:

wherein R is selected from the group consisting of hydrogen, lower alkyl, phenyl, p-methoxyphenyl, p-formylphenyl, p-carboxyphenyl, p-nitrophenyl, p-tolyl, p-benzodiacetate, bromo, amino, di-loweralkylamino, morpholino 2-(methylthio)-2-imidazolin-1-yl, phenylthio and phenylsulfonyl.

lino, 2-(methylthio)-2-imidazolin-1-yl, phenylthio and phenylsulfonyl.

2. The fungicidal composition according to claim 1, wherein the nitrothiadiazole is 2-(4-methoxyphenyl)-5-nitro-1,3,4-thiadiazole.

3. The fungicidal composition according to claim 1, wherein the nitrothiadiazole is 2-nitro-1,3,4-thiadiazole.

4. The fungicidal composition according to claim 1, wherein the nitrothiadiazole is 2-phenyl-5-nitro-1,3,4-thiadiazole.

5. The fungicidal composition according to claim 1, wherein the nitrothiadiazole is 2-bromo-5-nitro-1,3,4-thiadiazole.

6. A fungicidal method for controlling fungi which comprises applying to said fungi a fungicidal amount of a compound of the formula:

wherein R is selected from the group consisting of hydrogen, lower alkyl, phenyl, p-methoxyphenyl, p-formylphenyl, p-carboxyphenyl, p-nitrophenyl, p-tolyl, p-benzodiacetate, bromo, amino, di-loweralkylamino, morpholino 2-(methylthio)-2-imidazolin-1-yl, phenylthio and phenylsulfonyl.

7. A fungicidal method according to claim 6, wherein the nitrothiadiazole is 2-(4-methoxyphenyl)-5-nitro-1,3,4-thiadiazole.

8. A fungicidal method according to claim 6, wherein the nitroimidazole is 2-nitro-1,3,4-thiadiazole.

9. A fungicidal method according to claim 6, wherein the nitroimidazole is 2-phenyl-5-nitro-1,3,4-thiadiazole.

10. A fungicidal method according to claim 6, wherein the nitroimidazole is 2-bromo-5-nitro-1,3,4-thiadiazole.
